DESIGN FOR A CARRYING CASE

John F. Horton, Jr., Springfield, and Robert S. Lee, Jenkintown, Pa., assignors to Colonial Motors, Inc., a corporation of Pennsylvania

Application January 11, 1947, Serial No. 136,088

Term of patent 3½ years

(Cl. D87—5)

To all whom it may concern:

Be it known that we, John F. Horton, Jr. and Robert S. Lee, both citizens of the United States, and residents respectively of Springfield, county of Delaware, State of Pennsylvania, and Jenkintown, county of Montgomery, and State of Pennsylvania, have invented a new, original, and ornamental Design for a Carrying Case, of which the following is a specification, reference being had to the accompanying drawing, forming a part thereof, wherein:

Figure 1 is a perspective view of a carrying case showing our new design;

Figure 2 is a front elevational view thereof;

Figure 3 is a top edge plan view thereof; and

Figure 4 is a rear elevational view thereof.

We claim:

The ornamental design for a carrying case, as shown.

JOHN F. HORTON, JR.
ROBERT S. LEE.
